SOUND RECORD TABLET

Walter H. Miller, South Orange, N. J., assignor
to Thomas A. Edison, Incorporated, West
Orange, N. J., a corporation of New Jersey

Application June 2, 1932, Serial No. 614,922

10 Claims. (Cl. 274—44)

The present invention relates to sound-record tablets and more particularly to hollow cylindrical sound-record tablets such, for example, as are ordinarily used in connection with dictating machines or business phonographs, the invention being especially directed to an improved construction or formation of the bore of such hollow tablets.

In order to facilitate the application and removal of a hollow cylindrical record or tablet to and from a record support, and at the same time to provide for frictionally maintaining the record in proper position on the support, it has been found desirable to taper the longitudinal bore of the record and to provide said bore with some form of spaced bearing surfaces. Heretofore these bearing surfaces have usually been produced by grooving the bore of such a record 15 around the longitudinal axis of the record, like the rifling of a gun barrel. Various forms of rifling of the bore of the record have been resorted to by changing the pitch and/or the shape of the lands or projections. However, in all cases 20 the lands and grooves have been extended to the extremity of the larger end portion of the bore of the tablet to enable the core of the mold used in forming the tablet to be readily extracted from the latter after it sets. Such a rifled or grooved 25 record tablet is materially weakened, especially at its thinner end portion, and is likely, upon being applied to or removed from a record support, to be broken, cracked or so damaged as to be rendered unsuitable for further use.

The principal object of this invention is to produce a record tablet, having a suitably fluted bore, but wherein the above described weakening thereof is largely avoided, whereby the danger or likelihood of breakage or serious damage to the 30 tablet incidental to the operation of applying or removing the same from the record support is practically eliminated.

Another object of the invention is to so reinforce the thinner end of a rifled record of this 45 character as to avoid the necessity of any departure from the ordinary process of manufacturing such records, as well as any substantial changes in the form, size, or composition of the latter.

A further object of the invention is to provide 50 in a tablet such as described, a suitable re-enforcing liner in conjunction with my improved bore construction, said liner preferably having centralizing means whereby it may readily be embedded for a portion of its length concentrically 55 with the bore of the tablet.

Other and further features and objects of the invention will be obvious upon an understanding of the preferred embodiment about to be described or will be indicated in the appended claims. Also various advantages not referred to herein will occur to one skilled in the art upon employment of the invention in practice.

A preferred embodiment has been chosen for the purposes of illustration and description and is shown in the accompanying drawing, wherein:

Figure 1 is a central longitudinal cross sectional view of a record tablet in accordance with my invention;

Fig. 2 is a fragmentary view, similar to Fig. 1, of a record tablet provided with a self-centralizing re-enforcing liner;

Fig. 3 is an end view looking from the left in Fig. 1;

Fig. 4 is a fragmentary end view looking from the left in Fig. 2;

Fig. 5 is a sectional view taken on line 5—5 of Fig. 1;

Fig. 6 is a sectional view taken on line 6—6 of Fig. 2;

Fig. 7 is a view, partly in elevation and partly in section, of the molding apparatus showing the improved core for forming the bore of a record, and also showing clearly the manner in which a liner may be embedded in the record;

Fig. 8 is a sectional view of a record taken on a line corresponding to line 8—8 of Fig. 6; and

Fig. 9 is a sectional view of a record when on a line corresponding to line 9—9 of Fig. 6.

The sound record or tablet shown in Figs. 1, 3 and 5, is in the form of hollow cylinder. In the operation of recording on and reproducing from such a tablet or record, the latter is usually mounted on a mandrel or support designed to firmly and frictionally engage the bore of the tablet so as to hold the same for rotation with the mandrel and against longitudinal displacement thereon. This mandrel is tapered, and, consequently, the bore of the record is correspondingly tapered from the small end 2 to the large end 3. The taper is provided, among other reasons, to enable the tablet to be easily withdrawn from the core of the mold in which it is formed, and also so that the tablet may be more readily applied to and removed from the mandrel. To further facilitate the removal of the tablet from the mold core and the application and removal of the same to and from the mandrel, and also to provide ample bearing engagement between the mandrel and tablet for frictionally holding the tablet on the mandrel with

sufficient firmness, the bore of the tablet is provided with the helical lands, ribs or projections 4 and grooves 5.

The lands or ribs 4 and grooves 5 are produced in the molding of the tablet by a fluted core 6 (see Fig. 7). During the molding operation the core 6 is mounted on a suitable base 7 as is also the cylindrical mold shell 8 within which the core is centrally disposed. The upper end of the shell 8 is open and in producing a tablet, molten wax or wax-like material from which the tablet is to be formed is poured into the shell through this open end. After the said material sufficiently congeals, the shell 8 is first stripped from the formed record tablet, and the latter and the core are then separated by imparting relative rotary movement thereto. After the record is separated from the core, it is allowed to thoroughly set. The record is then reamed to make it more accurately fit the mandrel. In the reaming operation the inner or higher portions of the lands 5 are removed and the surface portion of the bore adapted to contact the mandrel is therefore increased.

From the foregoing, it is obvious that the rifling in the bores of records of the character described is highly desirable and that to dispense with such rifling would result in serious disadvantages. Consequently the present invention is meritorious as it remedies the above indicated weakness of such tablets due to the extension of the rifling or helical grooving to the thinner end of the tablets, while at the same time all of the advantages of the rifling or grooved construction are retained.

In a tablet produced in accordance with my invention, the rifling or grooving of the bore is preferably formed as shown in Figs. 1 and 5, with the bottom of each groove 5 for the greater portion of the length of the groove, inclined or tapered with respect to the axis of the tablet substantially in compliance with the taper of the bore of the tablet, but with the bottom of the portion 10 of each groove beyond the point indicated at A and adjacent the thinner end of the tablet, parallel or substantially parallel to the said axis. In other words, all points in the bottom of the portion 10 of each groove 5 are at substantially the same radial distance from the longitudinal axis of the record. Thus, the grooves 5 gradually decrease in depth from the points A to the points 11 (Fig. 1) where the bottoms thereof merge in the surface of the bore of the tablet. When a tablet has the bore construction just described, the core 6 of the mold may be readily extracted from the tablet after this latter has been formed, and the tablet may afterward be reamed in the manner hereinbefore set forth. Also as a result of such construction the tablet is appreciatively increased in strength at its thinner end without sacrificing any of the advantages due to the usual rifling or rib and groove construction.

The location of points A, at which the inclination of the bottom surfaces of the grooves 5 change, may be varied lengthwise of the bore of the record cylinder; depending upon the depth of the main portions of said grooves and the desired location of the vanishing or merging points 11. If the points A are shifted to the left, (Fig. 1) the vanishing points 11 of grooves 5 will be located nearer to the adjacent end of the cylinder, while if the points A are shifted to the right, the points 11 will be more remote from the said end of the cylinder. The forma-

tion of the bore of the tablet is, of course, governed by the construction of the core 6.

It is sometimes desirable that sound record tablets of the character herein described have re-enforcing liners molded or embedded therein. To produce such a re-enforced record I place a tapered or frusto-conical tube or liner 12, made of a stiff or semi-rigid and porous fabric or foraminous material, over the core 6 of the mold, as shown in Fig. 7. When the lands of the mold core which form the rifling or grooves in the bores of such tablets extend over the full length of the core, as is customary, such a tapered liner is readily held in accurate centralized position. However, in the practice of my invention, the lands 5' of the core 6 are necessarily changed so that the portions thereof between the points A' and the larger lower end of the core will produce the groove portion 10 in the bore of the tablet. To centralize the liner on the mold core 6 and in the record tablet, I proceed as follows:

The liner 12, referring particularly to Fig. 7, is preferably provided with a circumferential corrugation or crimp 13 which is formed at such a point lengthwise of the liner, that when the latter is properly disposed on the core 6 such corrugation will substantially correspond in position with the points where the lands 5' merge with the main conical surface portion of the core. The corrugation 13 may extend unbrokenly entirely around the liner or may be interrupted so as to comprise a plurality of spaced sections. The depth of this corrugation is such that when the liner is properly positioned on the core 6 it will, as shown in Fig. 7, be maintained concentrically thereon. Accordingly, the liner will be embedded in the tablet thereafter formed in the mold concentrically with the bore of such tablet and at a sufficient distance from the surface of said bore to permit the tablet to be properly reamed without interference from the liner and without mutilation of the latter other than the cutting away of part of said corrugation. Also, as seen in Fig. 2, an appreciable portion of the liner will be embedded in and re-enforce the thinner ungrooved end portion of the tablet. It will be understood that when the wax-like material of which the tablet is formed is poured, in a hot fluid condition, into the mold it will pass quite freely through the porous or foraminous material of the liner 12 into close engagement with the core 6.

It is to be understood that the terms "record" and "tablet" as used throughout this specification, are each intended to refer to a hollow cylindrical phonograph record tablet either before or after the sound recording has been formed thereon.

It is to be understood that various changes may be made in the herein described embodiments without departing from the spirit of my invention, and that all matter herein contained is to be interpreted as illustrative and not in a limiting sense.

Having thus described my invention, I claim: 140

1. A hollow cylindrical tablet having grooves in its bore extending longitudinally of the latter for the greater portion of its length, said grooves having corresponding end portions which decrease in depth toward the nearer end of the tablet and finally merge with the main surface of said bore at points spaced inwardly from but adjacent said end of the tablet. 145

2. A hollow cylindrical tablet having longitudinally extending grooves in its bore, said grooves 150

- having corresponding end portions which decrease in depth toward one end of the tablet and portions of substantially uniform depth respectively joining said end portions and extending 5 therefrom towards the other end of the tablet. 80
3. A hollow cylindrical tablet having a tapered bore provided with a plurality of similar longitudinally extending helical grooves, said grooves having main portions of substantially uniform 10 depth and portions adjacent one end which respectively join said main portions at one end of the latter and which decrease in depth from such main portions toward one end of the tablet. 85
4. A hollow cylindrical tablet having a tapering bore, said bore being provided with grooves which extend longitudinally thereof for the greater part of its length, said grooves having their corresponding end portions decreasing in 15 depth toward the nearer and larger end of said bore and finally merging with the main surface 20 of the bore at points spaced inwardly from but adjacent said larger end of the bore. 90
5. A hollow cylindrical tablet having longitudinally extending grooves in its bore, said grooves 25 having portions adjacent one end which decrease in depth towards one end of the tablet and which merge with the main surface of said bore at points spaced inwardly from but adjacent to the 30 said end of the tablet, and re-enforcing means embedded in a portion of the tablet corresponding to the said end portions of the grooves and extending beyond said grooves toward the said end of the tablet. 95
6. A hollow cylindrical tablet having a tapering bore provided with longitudinally extending 35 grooves, said grooves having portions adjacent one end which decrease in depth towards the thinner end of the tablet and which merge with 100
- 40
- 45
- 50
- 55
- 60
- 65
- 70
- 75
- the main surface of said bore at points spaced inwardly from but adjacent to its larger end, and re-enforcing means embedded in a portion of the tablet corresponding to the said end portions of the grooves and extending beyond said grooves towards the said thinner end of the tablet. 80
7. A hollow cylindrical tablet having a tapering bore, provided with longitudinally extending grooves, said grooves having one end thereof terminating at points spaced inwardly from but adjacent to the thinner end of the tablet, and re-enforcing means embedded in a portion of the tablet corresponding to a portion of the grooving in said bore, said means extending beyond said grooves toward the said thinner end of the tablet. 90
8. A hollow cylindrical tablet having grooves in its bore extending longitudinally of the latter for the greater portion of its length, said grooves terminating short of each end of the tablet and having end portions decreasing in depth toward one end only of the tablet which is adjacent such end portions. 95
9. A hollow cylindrical tablet having grooves in its bore extending longitudinally of the latter for the greater portion of its length, said grooves terminating short of each end of the tablet and having portions at one end which decrease in depth toward one end only of the tablet and which finally merge with the main surface of the bore. 100
10. A hollow cylindrical tablet having a tapered bore, said bore being provided with grooves extending longitudinally thereof for the greater portion of its length but terminating short of each end of the tablet, said grooves having corresponding end portions which decrease in depth 110 toward the larger end of said bore. 110
